UNITED STATES PATENT OFFICE

128,395

DESIGN FOR A LOOP ANCHORAGE FOR LUGGAGE HANDLES AND THE LIKE

Hyman G. Kates, New York, N. Y.

Application September 27, 1940, Serial No. 95,435

Term of patent 3½ years

To all whom it may concern:

Be it known that I, Hyman G. Kates, a citizen of the United States of America, residing at New York, New York, have invented a new, original, and ornamental Design for a Loop Anchorage for Luggage Handles and the like, of which the following is a specification, reference being had to the accompanying drawing, forming part thereof.

In the drawing:

Fig. 1 is a side elevational view of a loop an-

chorage for luggage handles and the like showing my new design, and

Fig. 2 is an end elevational view thereof.

The dominant features of the design reside in the portions shown in full lines.

I claim:

The ornamental design for a loop anchorage for luggage handles and the like, as shown and described.

HYMAN G. KATES.
